Application October 16, 1941, Serial No. 415,243

5 Claims. (Cl. 38—40)

1

My invention relates to garment pressing machines and includes in combination therewith a unitary cushioning device which will cushion the pressing lever on its upstroke and also cushion the pressing lever on its downstroke, preferably during the final portion of each stroke.

In garment pressing machines actuated by power, where cam or linkage systems have been employed to transmit the input power from the actuating motor to the pressing head, great difficulty has been experienced in having the pressing head travel with such velocity that unless its movement be cushioned it will tend to disarrange the garment being pressed, and great difficulty has also been experienced in the pressing lever coming to a sudden and abrupt stop at the end of the upstroke, making considerable noise, causing annoyance and unnecessary excessive wear on the machine. For these reasons, in association with such types of actuating mechanisms, it has been desirable to provide a cushioning means for cushioning the movement of the pressing lever and pressing head adjacent the end of its downstroke just prior to the contact with the garment and buck and also suitable cushioning means for cushioning the pressing head during the final portion of its upstroke. In the prior art, various types of cushioning devices have been employed, such as a separate cushioning device for the downstroke and a separate cushioning device for the upstroke, or complicated one or two-way shock absorbers.

An object of my invention, therefore, is to provide a single cushioning unit which will cushion the movement of the pressing lever and head during the final portion of its downstroke just prior to contact with the buck so as not to disarrange the garment being pressed, and which will also cushion the pressing lever and pressing head during the final portion of its upstroke. While my improved cushioning device may be also employed for cushioning other oscillatable members, particularly those which are not constantly oscillatable but which are positively moved by a separate motive power in each direction, the specific embodiment shown herein is particularly designed for use in garment pressing machines.

Further features of my invention relate to the provision of a single cushioning device comprising an oil check which will function on both the forward and backward movements of the oscillatable member, preferably during the end portion of each movement, and the means I employ to interconnect the same with the actuating means for the oscillatable member so that the oil check may

2

be loaded and function during each respective stroke of the oscillatable member in each direction, the specific means employed preferably comprising a toggle, which on the movement of the oscillatable member in either direction will function to move from an off-center position to a center position with its three pivot points aligned to raise the piston of the oil check with an upstroke for loading purposes and will then function on the continuation of said stroke of the oscillatable member in either direction to again move to an opposite off-center position so that the piston may actuate the flow of fluid through a restricted passage to function as an oil check during the remainder of such stroke of the oscillatable member in said respective direction.

Further objects of my invention relate to improvements in the specific cushioning device or oil check I preferably employ, which include an adjustable needle valve for the bypass orifice of the oil check and the provision, I believe for the first time, of a pressure relief valve or safety valve in said bypass orifice, and a specific type of spring actuated locking means for locking such an adjustable needle valve in any one of a plurality of selected adjusted positions.

Employing oil checks of the type employed in the prior art, particularly when starting up on cold mornings, the oil employed in the oil check has become too viscous for a ready flow through the restricted bypass orifice, resulting in breakage of parts of the oil check on such operation. Employing my improved pressure relief valve, however, I am able to provide a device which will so enlarge the restricted orifice of the bypass as to initially permit the flow of oil of any viscosity therethrough and which will automatically return to its desired adjusted position after the oil has been heated or transformed into the desired viscosity in use, it being also obvious that the pressure relief valve will similarly function if, through inadvertance, the adjustable needle valve has been left entirely closed. In addition, if attempts are made to tightly adjust the needle valve on its seat, the pressure relief spring will merely compress without any damage to the needle valve or its cooperating valve seat.

These and such other objects of my invention as may hereinafter appear will be best understood from a description of the accompanying drawings which illustrate a pressing machine equipped with my invention.

In the drawings,

Fig. 1 is a diagrammatic side elevation of a garment pressing machine constructed in accord-

ance with my invention, diagrammatically illustrating the functioning of the cushioning device or oil check I preferably employ and the actuating means for the same connected to the actuating mechanism for the pressing head, showing the pressing head, oil check and actuating means in the positions they assume when the pressing head is open substantially at the completion of the opening stroke of the pressing head.

Fig. 1^a is a diagrammatic view illustrating the positions that the parts of the oil check assume substantially at the initiation of the closing stroke of the pressing head, the pressing head and actuating means therefor being in the positions shown in Fig. 1.

Fig. 2 is a diagrammatic side elevation similar to Fig. 1 with the pressing machine actuated to a position aligning the three pivot points of the toggle in a center position with the pressing head three-quarters closed.

Fig. 3 is a diagrammatic side elevation of the parts shown in Figs. 1 and 2 with the garment pressing machine actuated to move the pressing head to a fully closed position, showing the position that the parts of the oil check assume substantially at the completion of the closing stroke of the pressing head.

Fig. 3^a is a diagrammatic view illustrating the positions that the parts of the oil check assume substantially at the inception of the opening stroke of the pressing head, the pressing head and actuating means therefor being in the positions shown in Fig. 3.

Fig. 4 is a diagrammatic view illustrating the three positions of the toggle, oil check piston and connecting lever shown respectively in Figs. 1, 2 and 3, illustrating the position shown in Fig. 1 in full lines, the position shown in Fig. 2 in dash lines and the position shown in Fig. 3 in dotted lines.

Fig. 5 is a chart illustrating the velocity of pressing head movement without action of the oil check in dash-dot lines, the action of the oil check in dotted lines and the composite graph of the velocity of press member with the action of the oil check, on both the down and up strokes of the pressing head of the garment pressing machine shown in Figs. 1-3, the dead center position of the aligned toggle pivots being assumed, as shown in Fig. 2, at substantially three-quarters of the movement of the pressing head during its downstroke and substantially one-quarter of the movement of the pressing head during its upstroke.

Fig. 6 is an enlarged vertical sectional view taken centrally of the improved type of oil check I preferably employ, showing the oil check piston substantially at the beginning of the downstroke thereof, and the by-pass restricting valve functioning as a pressure relief valve.

Fig. 7 is a vertical sectional view of the parts of the oil check shown in Fig. 6 substantially at the beginning of the upstroke of the piston and with the adjustable valve in a selected adjusted position in the bypass orifice.

Fig. 8 is a horizontal sectional view taken along the line 8-8 of Fig. 6.

Fig. 9 is a horizontal sectional view taken along the line 9-9 of Fig. 6.

In the drawings, wherein like characters of reference generally indicate like parts throughout, 10 generally indicates a garment pressing machine constructed in accordance with my invention. Said machine 10 has the usual frame 12 on which the pressing buck 14 is suitably

mounted. A pressing lever 16 is suitably pivoted as at 18 on another portion of the frame 12 having a pressing head 20 mounted as at 22 on the end thereof to be moved from the open position shown in Fig. 1 to the closed position shown in Fig. 3 in contact with said buck. It is thus obvious that the pressing head 20 is an oscillatable member moving or oscillating forth from the open position shown in Fig. 1 to the closed

position shown in Fig. 3, and moving or oscillating back from the closed position shown in Fig. 3 to the open position shown in Fig. 1. While, as stated, certain features of my invention may be employed to cushion the movement of any oscillatable member, they are particularly designed and adapted to cushion the movement of a pressing member, such as the pressing head 20, relatively oscillatable from open to closed positions and vice versa at the will of the operator.

10 In the garment pressing machine shown, means effective at the will of the operator are provided to actuate said oscillatable pressing member 20 to effect each of said closing and opening oscillating strokes. While any suitable type of means may be employed for actuating the pressing head 20 to and from positions into contact with said buck 14, I have shown a suitable fluid motor for this

15 purpose, in the embodiment shown comprising the cylinder 24 pivotally mounted as at 26 on a suitable point on said frame and having a piston 28 forced outwardly by fluid pressure, having a piston rod 30 connected to the input end of power transmitting means to move said pressing head.

20 While any suitable type of power transmitting means may be employed, I have shown in the drawings a suitable type of linkage means 32 for this purpose. In the embodiment shown, the linkage means includes a power applying lever 34 of the first class, pivotally mounted on a fixed point on the frame, as at 36, having a long arm 38 projecting downwardly therefrom and a short arm 40 projecting upwardly therefrom. I also have shown as part of said linkage system a second power applying lever of the first class 42 pivotally mounted as at 44 on a fixed point on said frame 12 and having a long arm 46 projecting rearwardly and a short arm 48 projecting forwardly therefrom. I also provide an interconnecting link 50 pivotally connected as at 52 to the short arm 48 of said second power applying lever 42 and pivotally connected as at 54 to the long arm 38 of said first power applying or booster lever 34. I also provide a triangular link member

25 56 having the apex or upper end thereof pivotally connected as at 58 to the power arm 60 of the pressing lever 16. I also provide a power transmitting link 62 having the upper end pivotally connected to the front end of the base 64 of said 30 triangular link 56 as at 66 and its lower end connected to the long arm 46 of said power applying lever 42 by the pivot 68. Another power applying link 70 has its upper end pivotally connected to the rear end of the base 64 of the triangular link 56, as at 72, and its lower end connected by the single point connection 74 to the short arm 40 of the power applying lever 34. It is thus apparent that during the outward stroke of the piston rod 30, said interconnecting levers

35 34 and 42 and links 50, 56, 62 and 70 joined together by the single point connections hitherto described function to lower the pressing head 20 from the open position shown in Fig. 1 to the closed position shown in Fig. 3. Means such as the spring 76 are provided to normally urge the

40 45 50 55 60 65 70 75

pressing lever 16 to raise the pressing head 20 to the open position shown in Fig. 1, the linkage system hitherto described functioning against the pressure of said spring to close the press and said spring means opens the press as soon as power is removed from the fluid motor 24. As stated, however, any suitable type of cam means or link means may be employed for the closing and opening strokes of the pressing head 20. If desired, in place of a prime mover or other type of motor, the actuating means for closing and opening the pressing head may be manually actuated by the foot or the hand of an operator. It is thus obvious that in the combination to be described, said just described linkage system and fluid motor and spring comprise means effective at the will of the operator to actuate said oscillatable pressing member 20 to effect said closing and opening oscillating strokes.

As stated hitherto, my invention also includes a device 78 for cushioning both the opening and closing strokes of said oscillatable pressing member 20. In the preferred embodiment shown, said cushioning means comprises the oil check means 78. Said oil check means includes a cylinder 80, a piston 82 reciprocatable therein having a check valve 84 thereon and a fluid movement restricting bypass 86 connected to said cylinder 80 on opposite sides of said piston 82 beyond the limits of movement of said piston 82 in each direction.

As stated, my invention includes in combination with the oil check means and other parts of the garment pressing machine hitherto described, means to move said oil check piston 82 back and forth during each respective closing and opening stroke of said oscillatable pressing member 20 so that said oil check means 78 may be loaded and also may function as an oil check on the movement of the oscillatable pressing member 20 in each direction. While said piston moving means may be actuated in any suitable manner, in the improved combination shown, said means is preferably actuated by the linkage or other actuating means 32 employed for oscillating the oscillatable member 20 in each direction. In the preferred embodiment, said means to move said piston 82 back and forth during each respective stroke includes a lever 88 pivotally mounted on the frame as at 90 having a power arm 92 and a work arm 94 suitably pivotally connected to the piston rod 96 of said piston 82 as at 98. While said work arm 94 may be connected to the end of the piston by a single pivot connection 98, in the embodiment shown I have pivotally connected the work arm 94 of said lever by the pivot pin 98 to an intermediate connecting link 100, having the opposite end thereof pivotally connected to the end of the piston rod 96 by the pivot connection 102. I also employ a pivotally mounted rocker arm 104 suitably pivotally connected to the frame. While this may be pivotally mounted on the frame in any suitable manner and pivoted by said actuating mechanism in said suitable manner, in the embodiment shown, said rocker arm 104 comprises an integral extension from the power applying lever 42 and the pivot point of said rocker arm 104 in this instance is identical to the pivot rod 44 of said power applying lever 42 and said pivotally mounted rocker arm 104 is connected to said actuating means by being an integral part of the power applying lever 42, so that said rocker arm 104 may move in synchronism with the oscillating movement of said oscillatable pressing member 20 in each direction. I also employ a connecting link 106 forming a tog-

gle with said rocker arm 104 pivotally connected to the power arm 92 of said lever 88 by the single point connection 108 and to said rocker arm 104 by the single point connection 110. It is thus obvious that said toggle 112 formed by said rocker arm 104 and connecting link 106 has three pivotable points of attachment, namely the pivot point 108 connecting said connecting link 106 to the power arm of said lever 88, the pivot point 44 of said rocker arm 104 and the interconnecting center pivot point 110 connecting the opposite end of said connecting link 106 with the opposite end of said rocker arm 104. An inspection of the drawings will show that the rocker arm 104 is brought into alignment on a dead center with said connecting link at the same predetermined point in both the closing and opening strokes of the oscillatable pressing member 20, raising the oil check piston 82 to its uppermost position shown in dash-dot lines in Figure 4, with said toggle pivot points 44, 110 and 108 aligned, as shown in Figs. 2 and 4, during the initial portion of the opening and closing strokes, as diagrammatically illustrated in Figs. 1-4, whereby, as shown in Figs. 2, 1^a, 3^a and 7, fluid will be passed through said check valve 84 on the upstroke of said oil check piston 82 during the initial portions of the closing and opening strokes of said rocker arm 104, link 106 and oscillating pressing member 20 up to said dead center, as shown in Fig. 2, to load said cylinder and said check valve 84 will be automatically closed on the downstroke of said oil check piston so that fluid will be passed through the restricted bypass 86 as shown in Figs. 3-4 to function as an oil check on the downstroke of the oil check piston 82 on the remainder of the closing stroke of said rocker arm 104, link 106 and oscillatable member 20 beyond said dead center shown in Fig. 2 to function as a cushioning means just prior to the contact of the oscillatable pressing member or pressing head 20 with the other pressing member or buck 14, as shown in Fig. 3, and also to function as an oil check on the downstroke of the oil check piston 82 on the remainder of the opening stroke of said rocker arm 104, link 106 and oscillatable member 20 beyond said dead center to function as a cushioning means prior to the termination of the opening stroke of said oscillating pressing member 20, as indicated in Fig. 1. As graphically set forth in Fig. 5, it will be observed that the dead center alignment of said toggle takes place at twelve-sixteenths of the downward movement of the press member, so that the oil check will function during the remaining one-quarter of the downstroke of the pressing head 20, but that on the upstroke of the pressing head 20, the dead center will be passed at four-sixteenths of the stroke, causing the oil check to function in a less abrupt manner during the remaining three-quarters of the upstroke of the pressing head, as graphically set forth in Fig. 5, so that employing my improved oil check the movements of the pressing member will be cushioned both on the downstroke and on the upstroke of the pressing member as graphically set forth by the full lines therein, illustrating the relative velocity of the press member modified by the oil check at the corresponding points in the up and down strokes, the action of the oil check and the unmodified action of the press member being shown respectively in dotted and dash-dot lines therein.

While as stated, my invention is particularly designed and adapted for use in checking the movement of an oscillatable member movable at the

will of the operator having means to positively oscillate said member in each direction, it may, if desired, be adapted to check the movements of any positively oscillated member in each direction in a machine having means to positively oscillate said member so that on each respective oscillating stroke of said member, said oil check may be loaded up to said dead center and discharged to function as an oil check beyond said dead center.

As stated hitherto, further features of my invention relate to improvements in the oil check itself, which, as stated employs a single piston and functions as an oil check for the movement of the oscillating member in either direction. Such a type of oil check includes the cylinder 80, the piston 82 having orifice means 83 therein, reciprocatable in said cylinder 80 having a check valve 84 mounted thereon urged in any suitable manner, preferably by the spring 85, to a position closing said orifice means 83 and the bypass line 86 connecting opposite ends of said cylinder 80 beyond the maximum positions of movement of said piston 82. While I preferably employ the spring 85 to actuate the check valve, its use, while desirable, is not necessary as the pressure of the oil will automatically urge the check valve to a closed position on the downstroke of the piston.

I have shown in the drawings, my improved type of oil check employing such an adjustable pressure relief valve having spring controlled means for selectively locking said valve in any one of several adjusted positions, and in order that its features may be more clearly understood, I will now describe the mechanism shown in the drawings in greater detail.

In the embodiment shown, I employ an outer chamber 114, which may be provided with a sight glass 116 in a side wall thereof, having a central horizontal partition 118 which may be conveniently located near the lower end thereof mounting a relatively small cylinder 80 in one portion thereof and having a bypass 86 in another portion thereof forming a bypass line having a portion forming the bypass orifice 87, which in the preferred embodiment shown is counter-sunk or tapered. The piston 82 is provided with a plurality of circumferentially aligned orifice means 83, as shown in Figs. 6, 7 and 9. In order to keep the cylinder 80 of relatively short height and to preserve its effectiveness, the piston 82 is provided with the annular flange 120 projecting downwardly therefrom, said piston 82 being reciprocatable in said cylinder 80 and having a piston rod 96 extending upwardly through a suitable hole 122 in the upper wall of said chamber, in the embodiment shown in a suitable bearing 124 detachably securable in said upper wall of the chamber 114 by the locking screw 126. Said piston rod 96 has a reduced portion 128 projecting downwardly through said piston 82 having a threaded lower tip 130 and having a flat check valve 84 for said orifice means 83 loosely mounted thereon, said piston 82 being non-movably mounted on said reduced portion 128 of the piston rod 96 with a force fit. A nut 132 is threaded on the threaded tip of said reduced portion 128 and a helical spring 85 is interposed between said nut 132 and check valve 84.

As stated, I have provided an adjustable needle valve 134 for said bypass orifice 87, and I provide mounting means for the valve rod 138 carrying said needle valve tip 134. In the preferred embodiment shown, said mounting means comprises a threaded hole 136 in the upper wall of said

chamber 114 directly in line with and above said bypass orifice 87. Said chamber has an annular flange 140 projecting upwardly around said hole forming a guide well 142 having a lower portion 144 of smaller bore and an upper portion 146 of larger bore forming the annular shoulder 148 between said bores. In the specific embodiment shown I provide an inner sleeve 150 having an externally threaded portion 152 engaging said

10 threaded hole 136, an enlarged portion 154 above said threaded portion 152 and a reduced portion 156 above said enlarged portion. The needle valve rod 138 is axially slidable within said inner sleeve 150 and has a threaded upper end 158 extending above said inner sleeve 150, an annular flange 160 near the lower end thereof and a conically pointed needle tip 134 forming a needle valve projecting within said bypass orifice 87. The safety valve feature of the adjustable valve 134 is provided by the helical safety spring 162 surrounding the lower end of said rod 138 and having its upper end abutting the lower end of said inner sleeve 150 and its lower end abutting said rod flange 160.

I also provide an outer sleeve 164 axially slideable on said inner sleeve within said well 142 and having an axial slot 166 in the lower end thereof and an annular flange 168 at the upper end thereof having a plurality of circumferentially aligned stop holes 170 (see Fig. 8 therein) in the upper surface thereof. A pin 172 projects radially inwardly from the lower portion of said well 142 within said axial slot 166 to provide means for preventing rotation of said outer sleeve 164. A helical locking spring 174 surrounds said outer sleeve 164 and has its lower end abutting the shoulder 148 of said chamber well 142 and its upper end abutting the outer sleeve flange 168.

I also provide a knurled adjusting knob 176 having its inner periphery frictionally engaging the reduced upper end 156 of said inner sleeve with a force fit so that rotation of said adjusting knob may also rotate said inner sleeve 150, said knob having a locking pin 178 projecting downwardly from the lower surface thereof selectively engageable with a respective stop hole 170 on the upper surface of the outer sleeve flange 168. It is thus obvious that said knurled adjusting knob 176 with its locking pin 178 movable on rotation of said adjusting nut out of a respective selected hole 170 in the flange 168 of said outer sleeve 164 forms manually operated means for adjusting said sleeve 150 and valve rod 138 movable therewith relative to said bypass orifice 87 on compression of the locking spring 174. The spring 174, yielding for this purpose to permit the locking pin 178 to move out of its inserted hole 170, forms a spring actuated locking device for locking said inner sleeve 150 and valve rod 138 movable therewith in a plurality of selected adjusted positions, relative to said bypass orifice 87, releasable for re-adjustment on substantial rotative pressure applied to said knurled adjusting knob 176, with the helical locking spring 174 compressing for this purpose. I also provide removable stop means comprising the internally threaded nut 180 detachably threaded on the threaded upper end 158 of said valve rod 138 to abut the upper surface of said knurled adjusting knob 176 to limit the downward movement of said rod 138, which nut 180 may also be adjusted, if it be desired, to vary the effective pressure of the safety spring 162.

In practice, the knurled adjusting knob 176 is rotated against the pressure of the locking spring 174 until the needle valve 134 is brought

into the desired position in the bypass orifice 87 with the locking pin 178 inserted in the closest adjacent locking hole 170. If for any reason an excessive fluid pressure should take place in the cylinder 80 in the lower portion of the chamber 114, the safety spring 162 may compress to permit the safety valve 134 to rise to an open position freeing and enlarging the orifice 87 for the discharge of fluid therethrough, as shown in Fig. 6. The piston 82 functions in the cylinder 80 in the manner hitherto described, the check valve 84 compressing the spring 85 for the passage of fluid through the orifice means 83 for loading purposes on the upstroke of the piston until the aforescribed off-center position of the links is achieved, when on the continuation of the closing or opening strokes of the oscillatable member the piston 82 is lowered within the cylinder 80, forcing fluid through the bypass line 86 and restricted orifice 87 thereof restricted by the needle valve 134, which may be inserted in selected adjusted amounts in said orifice 87 to regulate the amount of liquid which may be passed through said bypass line 86. The amount of the adjustable insertion of the needle valve 134 in the bypass orifice 87 therefor determines the restriction of said orifice, which controls the speed at which the oil may pass through the bypass and the amount of checking which may be provided on the circulation of oil therethrough.

As previously pointed out, the fact that the rocker arm 104 is mounted on the same pivot point 44 as a portion of the actuating linkage system for the oscillatable member is coincidental, and the rocker arm 104 may be mounted, if desired, on a separate fulcrum and suitably connected to the actuating mechanism in any suitable manner.

It is apparent that I have provided a novel type of pressing machine and cushioning device for use therein with novel structural features inherent in the oil check and with the advantages described above.

It is understood that my invention is not limited to the specific embodiment shown and that various deviations may be made therefrom without departing from the spirit and scope of the appended claims.

What I claim is:

1. In a pressing machine, a relatively stationary pressing member, a pressing member relatively oscillatable at the will of the operator from an open position to a position in pressing contact with the stationary pressing member on the closing stroke and from said closed position to said open position on the opening stroke, means effective at the will of the operator to actuate said oscillatable pressing member to effect said closing and opening oscillating strokes, and a device for cushioning said strokes of said oscillatable pressing member, comprising oil check means including a cylinder, a piston reciprocatable therein having a check valve therein adapted to be closed on the downward stroke of the piston and a piston rod and a fluid movement restricting bypass connected to said cylinder on opposite sides of said piston, a pivotally mounted lever having a power arm and a work arm pivotally connected to said piston rod, a pivotally mounted rocker arm connected to said actuating means to move said rocker arm in synchronism with the oscillating movement of said oscillatable pressing member in each direction, and a connecting link forming a toggle with said rocker arm pivotally connected to said piston rod and to said rocker arm brought into alignment on a dead center with said rocker arm at the same predetermined point in both the closing and opening strokes of said pressing member whereby fluid will be passed through said check valve on the upstroke of said oil check piston during the initial portions of the closing and opening strokes of said rocker arm, link and oscillating pressing member up to said dead center to load said cylinder, and fluid will be passed through said flow restricting bypass to function as an oil check on the downstroke of said oil check piston on the remainder of the closing stroke of said rocker arm, link and oscillatable member beyond said dead center to function as a cushioning means prior to the contact of the oscillatable pressing member with the other pressing member and on the remainder of the opening stroke of said rocker arm, link and oscillatable member beyond said dead center to function as a cushioning means prior to the termination of the opening stroke of said oscillating pressing member.

power arm of said lever and to said rocker arm brought into alignment on a dead center with said rocker arm at the same predetermined point in both the closing and opening strokes of said pressing member whereby fluid will be passed through said check valve on the upstroke of said oil check piston during the initial portions of the closing and opening strokes of said rocker arm, link and oscillating pressing member up to said dead center to load said cylinder, and fluid will be passed through said flow restricting bypass to function as an oil check on the downstroke of said oil check piston on the remainder of the closing stroke of said rocker arm, link and oscillatable member beyond said dead center to function as a cushioning means prior to the contact of the oscillatable pressing member with the other pressing member and on the remainder of the opening stroke of said rocker arm, link and oscillatable member beyond said dead center to function as a cushioning means prior to the termination of the opening stroke of said oscillating pressing member.

2. In a pressing machine, a relatively stationary pressing member, a pressing member relatively oscillatable at the will of the operator from an open position to a position in pressing contact with the stationary pressing member on the closing stroke and from said closed position to said open position on the opening stroke, means effective at the will of the operator to actuate said oscillatable pressing member to effect said closing and opening oscillating strokes, and a device for cushioning said strokes of said oscillatable pressing member, comprising oil check means including a cylinder, a piston reciprocatable therein having a check valve therein adapted to be closed on the downward stroke of the piston and a piston rod and a fluid movement restricting bypass connected to said cylinder on opposite sides of said piston, a pivotally mounted rocker arm connected to said actuating means to move said rocker arm in synchronism with the oscillating movement of said oscillatable pressing member in each direction, and a connecting link forming a toggle with said rocker arm pivotally connected to said piston rod and to said rocker arm brought into alignment on a dead center with said rocker arm at the same predetermined point in both the closing and opening strokes of said pressing member whereby fluid will be passed through said check valve on the upstroke of said oil check piston during the initial portions of the closing and opening strokes of said rocker arm, link and oscillating pressing member up to said dead center to load said cylinder, and fluid will be passed through said flow restricting bypass to function as an oil check on the downstroke of said oil check piston on the remainder of the closing stroke of said rocker arm, link and oscillatable member beyond said dead center to function as a cushioning means prior to the contact of the oscillatable pressing member with the other pressing member and on the remainder of the opening stroke of said rocker arm, link and oscillatable member beyond said dead center to function as a cushioning means prior to the termination of the opening stroke of said oscillating pressing member.

3. A device for checking the oscillating movement of a positively oscillated member in each direction in a machine having means to positively oscillate said member, comprising oil check means including a cylinder, a piston reciprocatable

therein having a check valve therein adapted to be closed on the downward stroke of the piston and a piston rod and a fluid movement restricting bypass connected to said cylinder on opposite sides of said piston, a pivotally mounted lever having a power arm and a work arm pivotally connected to said piston rod, a pivotally mounted rocker arm, means connected to the means for oscillating said member to move said rocker arm in synchronism with the oscillating movement of said member in each direction, and a connecting link forming a toggle with said rocker arm, pivotally connected to the power arm of said lever and to said rocker arm, brought into alignment on a dead center with said rocker arm at the same predetermined point in each stroke of the oscillating member in each direction whereby fluid will be passed through said check valve on the upstroke of said oil check piston during the initial portion of each stroke of said rocker arm, link and oscillating member in either direction beyond said dead center.

4. A device for checking the oscillating movement of a positively oscillated member in each direction in a machine having means to positively oscillate said member, comprising oil check means including a cylinder, a piston reciprocatable therein having a check valve therein adapted to be closed on the downward stroke of the piston and a piston rod, and a flow restricting bypass connected to said cylinder on opposite sides of said piston, a pivotally mounted rocker arm connected to the means for oscillating said member to move said rocker arm in synchronism with the oscillating movement of said member in each direction, and a connecting link forming a toggle with said rocker arm, pivotally connected to said piston rod and to said rocker arm, brought into alignment on a dead center with said rocker arm at the same predetermined point in each stroke of the oscillating member in each direction whereby fluid will be passed through said check valve on the upstroke of said oil check piston during the initial portion of each stroke of said rocker arm, link and oscillating member in either direction up to said dead center to load said cylinder and fluid will be passed through said flow restricting bypass to function as an oil check on the downstroke of said oil check piston on the remainder of each stroke of said rocker arm, link and oscillating member in either direction beyond said dead center.

cillating member in either direction beyond said dead center.

5. A device for checking the oscillating movement of a positively oscillated member in each direction in a machine having means to positively oscillate said member, comprising oil check means including a cylinder, a piston reciprocatable therein having a check valve therein adapted to be closed on the downward stroke of the piston and a piston rod, a pivotally mounted rocker arm connected to the means for oscillating said member to move said rocker arm in synchronism with the oscillating movement of said member in each direction, and a connecting link forming a toggle with said rocker arm, pivotally connected to said piston rod and to said rocker arm, brought into alignment on a dead center with said rocker arm at the same predetermined point in each stroke of the oscillating member in each direction whereby fluid will be passed through said check valve on the upstroke of said oil check piston during the initial portion of each stroke of said rocker arm, link and oscillating member in either direction up to said dead center to load said cylinder and fluid will be passed through said flow restricting bypass to function as an oil check on the downstroke of said oil check piston on the remainder of each stroke of said rocker arm, link and oscillating member in either direction beyond said dead center.
